SELF-LATCHING ELECTRIC PLUG

Louis Frank, Fellows, Calif.

Application September 20, 1943, Serial No. 503,042

2 Claims. (Cl. 173—343)

1

My invention relates to electric plugs particularly of the type having two parts with contact prongs or fingers carried by one part, and adapted to enter pockets or recesses in the other part, and the principal object of my invention is to provide plugs of the character referred to with simple means for automatically securing the parts to each other in assembled position and the securing means being capable of convenient manual manipulation so as to enable the parts of the plug to be readily separated.

It very frequently happens that the two part plugs used in current conductors to floor lamps, electrically operated machines, and electrically operated household equipment become accidentally separated due to pulling strains developed for one reason or another and impressed on the conductors to which the plug parts are connected, and my invention is especially designed to prevent the accidental separation of the parts of the connecting plugs used in such conductors.

A further object of my invention is to provide two part electric plugs with latching means which is simple in construction, inexpensive of manufacture and which may with little change be readily combined with the conventional forms of two part plugs now in general use.

With the foregoing and other objects in view, my invention consists in certain novel features of construction and arrangement of parts which will be hereinafter more fully described and claimed and illustrated in the accompanying drawings, in which:

Fig. 1 is a top plan view of a two part plug equipped with my securing means.

Fig. 2 is a vertical section taken approximately on the line 2—2 of Fig. 1.

Fig. 3 is a horizontal section taken approximately on the line 3—3 of Fig. 2.

Fig. 4 is a sectional view similar to Fig. 2 and showing a modified form of the securing means.

Fig. 5 is an elevational view of a part of a conventional electric socket and showing the same equipped with means for securing the inserted prongs of a plug.

Fig. 6 is an enlarged vertical section taken on the line 6—6 of Fig. 5.

Fig. 7 is an enlarged detail section taken on the line 7—7 of Fig. 5.

Fig. 8 is a perspective view of a contact prong or finger and showing the same recessed for the reception of the securing means.

Fig. 9 shows end elevational views of contact prongs or fingers of different shapes.

Fig. 10 is a detail section showing a metal in-

sert which is engaged by the hook end of the latching means.

Fig. 11 is a top plan view of a two part plug and showing a modified form of the securing means.

Fig. 12 is a vertical section taken on the line 12—12 of Fig. 11.

Fig. 13 is a vertical cross section taken on the line 13—13 of Fig. 11.

Referring by numerals to the accompanying drawings, and, particularly, Figs. 1, 2 and 3 which illustrate a preferred embodiment of my invention, 10 designates the plug member which carries a pair of spaced contact prongs or fingers 10^a and which latter are adapted to enter openings 10^b in a separately formed plug member 10^c to engage contacts located in said member 10^c in accordance with conventional practice. Both parts 10 and 10^c of the plug are formed of insulating material. Plug member 10 is provided with the usual centrally arranged aperture 11 for the accommodation of the electric conductors leading to said plug and a corresponding aperture 12^a for conductors is formed in plug member 10^c.

Formed in plug member 10 to one side of the center therein and in longitudinal alignment with one of the openings 10^b in plug member 10^c is an opening 12, and formed in the upper portion 30 of one of the side faces of said opening are recesses 18.

Fulcrumed at 14 on one of the prongs 10^a, which projects into the opening 10^b below said opening 12, is an arm 13 provided on its upper end with a head 17 of insulation and projecting from the side face of said head and adapted to occupy either one of the notches 18, is a lug 17^a. Formed on the lower end of arm 13 is a hook 15 which is adapted to engage against a shoulder 16^a formed in the upper end of a groove 16 which latter is formed in the plug member 10^c along the lower portion of the opening 10^b therein.

Arm 13 is formed of resilient metal and under normal conditions with said arm lying flat against the prong or finger 10^a, lug 17^a occupies one or the other of the notches 18, thus maintaining hook 15 in or out of engagement with shoulder 16^a. When the parts of the plug are to be secured to each other in connected arrangement, arm 13 is manipulated and shifted into a neutral position on the prong 10^a, thus permitting both prongs carried by the plug member 10^a to be inserted in the openings 10^b in plug member 10^c and after such insertion, the head 17 on arm 55 13 is engaged and flexed so as to withdraw lug

^{17a} from the notch ¹⁸ in which it rests and said arm ¹³ is swung upon its axis ¹⁴ thereby positioning hook ¹⁵ beneath shoulder ^{16a} as illustrated in Fig. 2, and thus the parts of the plug are secured in assembled relation.

In Fig. 4, an arm ^{13a}, practically identical with arm ¹³ and pivoted at ^{16a} to one of the contact fingers, is provided on its upper end with a head ^{17a} of insulation and interposed between the upper portion of said arm and the plug body ¹⁰, at one side of the opening ¹² therein, is an expansive coil spring ¹⁹ which normally maintains said arm ¹³ in position so that the hook ^{15a} on the lower end thereof is in engagement with the shoulder ^{16a}.

In Figs. 5, 6 and 7, I have illustrated a conventional form of plug connector which includes a body member ^B having internally arranged pairs of contact plates ^P for the reception of contact pins or fingers ²¹ carried by plug member ²³. The upper portions of the contact fingers ²¹ are provided with an undercut shoulder or shoulders, such as ^{21a}. A latching arm ²⁰ is pivoted at ^{20a} within plug body ^B, and the upper end of said arm, which projects through an opening in the upper portion of plug body ^B is provided with a head ^{20b} of insulation. A coil spring ^{20c} arranged between the upper portion of arm ²⁰ and an adjacent portion of body ^B yieldingly resists outward swinging movement of the upper ³⁰ portion of said arm.

The lower end of arm ²⁰ terminates in a hook ²², which passes through an aperture ^{22a} formed in one of the contact plates ^P, and engages beneath shoulder ^{21a}, thus securing the parts of the plug coupling in assembled relation as illustrated in Figs. 5 and 6.

To disengage hook ²² from its position beneath the shoulder ^{21a}, the head ^{20b} on the upper end of arm ²⁰ is engaged and said arm is swung on its axis so as to move hook ²² out of engagement with the shoulder ^{21a} and which action results from the bearing of the curved edge ^{22b} of said hook with the edge of plate ^P to one side of the opening ^{22a} therein. (See dotted lines Fig. 7.) Inasmuch as arm ²⁰ is formed of resilient metal, its lower portion may flex outwardly when the releasing action as just described is accomplished.

In Fig. 8 I have shown a modified form of the contact prong or finger, and in this modification, the finger ²⁴ is provided near its outer end with a recess ²⁵ for the reception of the hook ²² on the end of the arm ²⁰.

In Fig. 9 I have shown a contact prong or finger ^{21x} which is square in cross section, also a contact finger ^{21z} which is oblong in cross section.

The modified construction illustrated in Figs. 10, 11, 12 and 13 includes plug members ³⁰ and ³¹ and the external surface of member ³¹ may be threaded for insertion in a threaded socket or provided with a threaded shell of such metal as ³². Formed in plug member ³⁰ is a recess ³³ in

which is secured one end of a contact prong or finger ³⁴ which latter projects through a slot into an opening ³⁵ in plug member ³¹.

Pivoted on the upper portion of finger ³⁴ is an arm ³⁶ provided on its upper end with a head ³⁷ of insulation and projecting from said arm between said head and the pivot for said arm, is a finger ³⁸ which bears on an expansive coil spring ³⁹ seated in member ³⁰ below the opening ³³ therein. Formed on the lower end of arm ³⁶ is a hook ⁴⁰ which, when the two parts of the plug are assembled, engages beneath a shoulder ⁴¹ formed in the upper end of opening ³³.

As a result of the construction just described, the hook ⁴⁰ will engage beneath shoulder ⁴¹ when the two parts of the plug are assembled, thus securely maintaining the said parts in assembled relation, and to disconnect the parts of the plug, it is only necessary to engage head ³⁷ and swing arm ³⁶ against the resistance offered by spring ³⁹ until hook ⁴⁰ is disengaged from shoulder ⁴¹. Upper plug member ³⁰ carries a contact finger ⁴², a companion to finger ³⁴.

In Fig. 10 I have illustrated the shoulder ⁴¹ provided with a small insert ⁴² of metal located so that it is engaged by hook ⁴⁰ when the parts of the plug are assembled, thus eliminating wear upon that particular portion of the shoulder with which the hook makes contact. This construction may be used on the shoulders ^{16a} in the forms of plugs shown in Figs. 2 and 3.

Thus it will be seen that I have provided an electric plug part securing means which is simple in structure, inexpensive of manufacture and very effective in performing the functions for which it is intended.

It will be understood that minor changes in the size, form and construction of the various parts of my improved electric plug may be made and substituted for those herein shown and described without departing from the spirit of the invention, the scope of which is set forth in the appended claims.

I claim as my invention:

1. The combination with a two part electric plug connector, one of the parts of which is provided with a contact finger, the other part being provided with an opening for the reception of said finger, of an arm pivoted on said contact finger, a hook on the lower end of said arm, there being a shoulder formed in the body of the member having said contact finger receiving opening, which shoulder is adapted to be engaged by said hook, a head of insulating material on the upper end of said arm, and there being recesses formed in the plug member carrying the prong for receiving a portion of said head and thereby maintaining said arm in different positions.

2. The combination as set forth in claim 1 with an insert of wear resisting material on that portion of the shoulder that receives said hook.

LOUIS FRANK.
